CLAIM

The ornamental design for a food punnet as shown and described.

DESCRIPTION

FIG. 1 is a front, bottom, and left-side perspective view of a food punnet, showing our new design;

FIG. 2 is a front, bottom, and right-side perspective view thereof;

FIG. 3 is a rear, bottom, and right-side perspective view thereof;

FIG. 4 a rear, bottom, and left-side perspective view thereof;

FIG. 5 is a front elevational cross-sectional view thereof

taken in the direction of the cut line indicated 5-5 in FIG. 6;

FIG. 6 is a top plan view thereof;

FIG. 7 is a bottom plan view thereof;

FIG. 8 is a front elevational view thereof; and,

FIG. 9 is a left-side elevational view thereof.

A rear elevational view thereof is identical to the front elevational view thereof.

A right-side elevational view thereof is identical to the left-side elevational view thereof.

The broken line portions of the figure drawings are included to show unclaimed environment only and form no part of the claimed design.

1 Claim, 9 Drawing Sheets
